UNITED STATES PATENT OFFICE.

ELAINE JOURNET, OF NEW YORK, N. Y.

DESIGN FOR A HANDKERCHIEF.

Application filed October 25, 1926. Serial No. 19,468. Term of patent 7 years.

To all whom it may concern:

Be it known that I, ELAINE JOURNET, a citizen of United States, and a resident of the city of New York, borough of Manhattan, in the county and State of New York, United States of America, have invented a new, original, and ornamental Design for a Handkerchief, of which the following is a specification, reference being had to the accompanying drawing, forming part thereof.

Fig. 2 is an edge view of the handkerchief.

I claim:

The ornamental design for a handkerchief, substantially as shown.

ELAINE JOURNET.
